UNITED STATES PATENT OFFICE.

CHARLES R. BIRDSEY, OF HINSDALE, ILLINOIS, ASSIGNOR TO UNITED STATES GYPSUM COMPANY, OF CHICAGO, ILLINOIS, A CORPORATION OF ILLINOIS.

PLASTER BOARD.

Original application filed January 2, 1920, Serial No. 348,940. Divided and this application filed January 3, 1921. Serial No. 434,650.

To all whom it may concern:

Be it known that I, CHARLES R. BIRDSEY, a citizen of the United States, residing at Hinsdale, in the county of Du Page and State of Illinois, have invented certain new and useful Improvements in Plaster Board (Case B—2), of which the following is a description.

My invention belongs to that general class 10 of devices known as plaster board or the like, and relates particularly to an improved board which will be simple, convenient, substantial, durable, satisfactory and efficient, and which may be economically and accurately manufactured. The invention relates 15 particularly to a type of board in which the plaster, plaster Paris or plastic material body is substantially enclosed on one or both opposite or other edges, as well as on the 20 face sides, and in which the edges may be perfectly formed to conform to a definite specification as to size or angle. Many other objects and advantages of the construction herein shown and described will be obvious 25 to those skilled in the art from the disclosures herein given.

To this end my invention consists in the novel construction, arrangement and combination of parts herein shown and described, and more particularly pointed out 30 in the claims.

In the drawings, wherein like reference characters indicate like or corresponding parts,

35 Figure 1 is a sectional view through a portion of a plaster board embodying the invention;

Figure 2 is a similar view of a modified form of this invention.

40 Figure 3 is a similar view of another modification.

Figure 4 is a perspective view of a portion of the board shown in Figure 1.

It may be mentioned that the present application is a divisional application of my application Serial No. 348,940, filed January 2, 1920, which matured into Patent 1,395,031 on October 25, 1921.

Referring to the drawings, 1 represents a 50 body of suitable material, as for example plaster, plaster Paris or any equivalent for the purpose which may be handled, preferably in a plastic state and thereafter allowed to set or harden. The body is enclosed

between the covering sheets 2 and 3 of suitable material, and in this connection it may be mentioned that I have found paper of the desired weight and thickness very satisfactory for the purpose. 55

In this type of board one sheet, as shown sheet 3, is flanged or folded over to enclose an edge portion 4 at one or both sides, the same being preferably scored at 6 so as to form a uniform corner, as shown. The other covering sheet, as shown sheet 2, is preferably of a width to form an overlapping end portion or flange 5 overlying the other flange on the other sheet at one or both sides. The sheets may be similarly formed at the opposite side of the board as shown in Figure 2 or integrally, or otherwise formed at 7, Figure 1. Obviously, it is immaterial as to which flange is on the inside or outside, and where so constructed at both edges, the flange of one sheet at one edge might be on the inside, and be on the outside on the opposite side of the board. It is also immaterial as to how much the edge portions overlap inasmuch as each one overlaps the other, and the edges of the board will be perfectly and completely sealed. The extreme edge of the outer flange 5 may extend flush with the extreme edge of the cover sheet 3 if so desired, as shown in Figure 3. In constructing this type of board, while the overlying or overlapping edges 4 and 5 may be secured together in any suitable manner, ordinarily enough plaster or plaster Paris, if the body is constructed of this or its equivalent, may flow up between the two upturned portions 4 and 5, securely sealing the same and maintaining the parts together. The board may be manufactured by such method, process or machinery as may be found suitable for the purpose. 85 90 95

It will be noted that in all of these constructions, the edge is substantially completely enclosed, and as before mentioned, this may be at one or both sides. If the two sheets are integral and wrapped or folded over one edge, or it is desired to enclose only one edge, then this construction might only be employed at one edge, the opposite edge being different. The resulting product is produced with a finished and smooth edge 100 and at a perfect desired angle, the board being uniform in width throughout its length. The completed product has many advan-

tages, including increased strength and durability, and an improved appearance. In case of handling, the edges are protected, and there is no breaking away nor sifting 5 out or powdering of the body at the edge. It will be noted that there is a double thickness of covering sheets at the extreme edge of the board.

Having thus described my invention, it is 10 obvious that various immaterial modifications may be made in the same without departing from the spirit of my invention; hence I do not wish to be understood as limiting myself to exact form, construction, 15 arrangement and combination of parts herein shown and described, or uses mentioned.

What I claim as new and desire to secure by Letters Patent is:

1. A plaster board of the kind described 20 comprising a body and a cover sheet arranged at each face side thereof, one of said sheets folded over the edge of the body and adhering thereto, and the other sheet folded over and extending to adjacent the first mentioned sheet and secured thereto.

2. A plaster board of the kind described comprising a body and a cover sheet arranged at each face side thereof, one of 30 said sheets folded over the edge of the body and adhering thereto, and the other sheet folded over the folded over portion of the first mentioned sheet.

3. A plaster board of the kind described comprising a body and a cover sheet extending over each face side thereof, said 35 sheet at one face folded over the edge of the body and adhering thereto, and the sheet at the other face folded over and overlying the other folded portion and secured thereto.

4. A plaster board of the kind described

comprising a body and a cover sheet extending over each face side thereof, said sheet at one face folded over the opposite edges of the board and adhering thereto, 45 and the sheet at the other face folded over and overlying the other folded portions and secured thereto.

5. A plaster board of the kind described comprising a body enclosed on opposite faces thereof, the enclosing sheets folded over and overlapping each other at one of the edges of the board and each terminated short of the opposite side face.

6. A plaster board of the kind described comprising a body enclosed on opposite faces thereof, the enclosing sheets folded over to overlap each other at one of the edges of the board and secured together thereat and each terminated short of the 60 opposite side face.

7. A plaster board of the kind described comprising a body enclosed on opposite side faces, the enclosing sheets folded over at the corners of one edge of the body to overlap each other along the face of the edge of the body, the folded over portions each terminated short of the cover sheet body on the opposite side face.

8. A plaster board of the kind described 70 comprises a body enclosed on opposite faces thereof, the enclosing sheets folded over and overlapping each other at the opposite edges of the board and each terminated short of the opposite side face.

In testimony whereof, I have hereunto signed my name in the presence of two subscribing witnesses.

CHARLES R. BIRDSEY.
